UNITED STATES PATENT OFFICE

HENRY KONDOLF, OF NEW YORK, N. Y., ASSIGNOR TO SOUTHERN KRAFT CORPORATION,
A CORPORATION OF DELAWARE

BOX AND METHOD OF MAKING SAME

Application filed November 19, 1930. Serial No. 496,658.

My invention is particularly adapted for use in the manufacture of boxes from fibre board and comprises the blank used, the method of forming the box and the improvements secured in the box when it is erected.

An object of my invention is to provide a blank which is simple and easy to manufacture, causes a minimum of waste of material, and which can be readily set up or erected into box form by unskilled labor and when so erected possesses a maximum of rigidity and a finished substantial appearance.

Another object of my invention is to provide simple and positive locking means which are a part of and cooperate with the box members to positively lock the same in erected position.

My invention provides a blank which can be coated when flat with an adhesive such as glue, silicate of soda, collodion or a heated asphaltum compound, and then erected into a laminated box structure with the adhesive coating between the box members.

My invention provides a blank in which the outer lamination may be folded into box section form and thereafter the members comprising the inner lamination may be individually folded into position within the outer section until the box is completed. A double ply box is thus obtained.

My construction eliminates much of the difficulty experienced in the manufacture of laminated boxes because a precise fit of the separate box sections is not necessary and the difficulty of assembling one series of members as a whole with another series of members already erected into box section form is largely obviated. This becomes of great importance when using a blank or blanks coated with an adhesive, which from its nature is sticky and resists the sliding of one member over another member. Likewise my construction is of marked advantage when using a reinforcing piece or blank between the laminations of the box, and permits the use of a thick or bulky reenforce blank without difficulty.

Due to the ease and accuracy with which my improved box may be erected, the slight resistance encountered by the box members in

going into proper position, and the provision made to automatically lock the members into position it is unnecessary to press the layers of my box over a form or die after folding, which is the usual practice with other types of laminated boxes. This affords a great saving in machinery and equipment.

My box is well adapted for use as a cigar box, since it has a finished appearance and when constructed with a heavy reenforce blank, provides a wall of about the thickness used in wooden cigar boxes. For this purpose I prefer to use a flat wooden cover hinged to the box and thus obtain a cigar box which is an exact replica of a wooden box, and has as much or more rigidity and a great deal more strength to resist breakage.

In the accompanying drawings, Fig. 1 is a plan view of one form of my improved blank, cut and creased or scored, so that it can be erected to produce a box, and provided with members for use in automatically locking the parts of the box when same are set up in box form. Fig. 2 is a plan view of one form of reenforce blank which may be used in connection with my improved blank. Fig. 3 is a perspective view of the reenforce blank shown in Fig. 2. Fig. 4 is a perspective view of the blank shown in Fig. 1, partly folded. Fig. 5 is a perspective view of the completed box. Fig. 6 is a perspective view to a greatly enlarged scale of one corner of the box shown in Fig. 5 to make clear the action of the automatic locking means.

In the drawings like reference numerals refer to like parts. As illustrated in Fig. 1 a fibre board sheet is provided with the parallel creases 10 and 11 and with the parallel creases 12 and 13 at right angles thereto. These four creases 10, 11, 12 and 13 define the bottom member 14 of the outer lamination of the box. The crease 15 and the parallel creases 16 and 17 define one end wall 18 of the outer lamination of the box. The crease 19 and the creases 20 and 21 define the opposite corresponding end wall 22 of the box. The end wall 18 is hinged to the bottom 14 along the crease 10 and the end wall 22 is hinged to the bottom 14 along the crease 11. The crease 23 and the cuts 24 and 25

define one side wall 26 of the outer lamination of the box. The crease 27 and the cuts 28 and 29 define the opposite corresponding side wall 30 of the box. The side wall 26 is hinged to the bottom 14 along the crease 12 and the side wall 30 is hinged to the bottom 14 along the crease 13. The member 31 between the creases 23 and 32 and the member 33 between the creases 27 and 34 form the upper edges of the side walls of the box. The member 35 between the creases 15 and 36 and the member 37 between the creases 19 and 38 form the upper edges of the end walls of the box. The member 39 between the creases 34 and 40 is hinged to the member 33 along the crease 34 and forms one inner side wall of the box. The member 41 between the creases 32 and 42 forms the opposite corresponding inner side wall of the box. The member 42 hinged to the member 39 along the crease 40 forms a part of the inner bottom of the box and the member 43 hinged to the member 41 along the crease 42 forms the other part of the inner bottom of the box. The member 44 hinged to the member 35 along the crease 36 forms one inner end wall of the box. The member 45 hinged to the member 37 along the crease 38 forms the opposite corresponding inner end wall of the box. The corner-piece 46 is hinged to the end wall 18 along the crease 16 and the corner-piece 47 is hinged to the end wall 18 along the crease 17. The corner-piece 48 is hinged to the end wall 22 along the crease 20 and the corner-piece 49 is hinged to the end wall 22 along the crease 21.

It will be noted that the edge 50 of the member 44 is longer than the crease 36. Similarly the edge 51 of the member 43 is longer than the crease 42. The edge 52 of the member 42 is longer than the crease 40 and the edge 53 of the member 45 is longer than the crease 38. This greater length in each case provides the additional stock desired to secure the automatic locking of all of the members of the box when the same is erected.

Figs. 2 and 3 illustrate a form of reenforce blank, 54 represents the bottom member having attached thereto the side wall members 55 and 56. Attached to the end of the side wall members are the end wall members 57, 58, 59 and 60.

Fig. 4 shows the blank of Fig. 1 in partly folded condition. The outer end walls 18 and 22 have been brought up into position and the corner pieces 46, 47, 48 and 49 have been folded into position. At this point the bottom 54 of the reenforce blank shown in Fig. 3 would be superimposed upon the bottom 14 of the partly folded blank with the side and end walls of the reenforce lying within the enclosure formed by the end walls 18 and 22 and the corner pieces 46, 47, 48 and 49. The outer side walls 26 and 30 are now

brought up to position and the inner side walls 41 and 39 are folded over the adjacent corner pieces and the side walls of the reinforce blank. Placing the inner side walls in position will bring the inner bottom section 43 and 42 into position on top of the bottom 54 of the reenforce blank. The inner end walls 44 and 45 are now folded over the end walls of the reenforce blank and pressed back at the corners until the inner end walls snap back of the inner side walls as shown in detail in Fig. 6. This completes the folding and locking of the blank into the finished box, shown in Fig. 5.

Referring to Fig. 6 it will be noted that the length of the edges 51 and 52 of the abnormal inner bottom members 43 and 42 causes the same to project under the edge 50 of the inner end wall member 44 and this locks the bottom members into position. Likewise the length of the edge 50 of the abnormal inner wall member 44 causes this edge to project past the inner side wall members 39 and 41 and this locks the inner end wall members into position.

I claim:

1. A box blank comprising an outer bottom member provided with four edges and connected along two oppositely disposed edges with two outer side wall members and along the two remaining edges with two outer end wall members, each of said outer side wall members carrying an inner side wall member and a portion of an abnormal inner bottom member and each of said outer end wall members carrying two corner pieces and an abnormal inner end wall member, said inner end wall members cooperating with said inner bottom members and said inner side wall members as described to lock all members of the box in position when said blank is erected into box form.

2. A laminated box formed from an integral blank and comprising an outer bottom member, outer side wall members and outer end wall members; each of said outer end wall members carrying along its vertical edges corner pieces adapted to fold within the outer side wall members and an abnormal inner end wall member adapted to fold parallel to said outer end wall member; each of said outer side wall members carrying serially an inner side wall member and an abnormal inner bottom member, said inner side wall members being adapted to overlap said corner pieces and fold parallel to said outer side wall members when said bottom members are positioned; said inner end wall members and inner bottom members being adapted to cooperate with each other and with said inner side wall members as described to automatically lock all said box members in position in the erected box; and a reenforce blank held between said inner and outer box members.

3. A laminated box formed from an integral blank and comprising an outer bottom member, outer side wall members, and outer end wall members; each of said outer end wall members carrying along its vertical edges corner pieces adapted to fold within the outer side wall members and an abnormal inner end wall member adapted to fold parallel to said outer end wall member; each of said outer side wall members carrying seriatim an inner side wall member and an abnormal inner bottom member, said inner side wall members being adapted to overlap said corner pieces and fold parallel to said outer side wall members when said bottom members are positioned, and said inner end wall and inner bottom members being adapted to cooperate with each other and with said inner side wall members as described to automatically lock all box members in position in the box.

4. The combination in a laminated box, for the purpose of locking all the members thereof into erected position as described, of inner end wall members of greater width than the normal inside width of the box and inner bottom members of greater length than the normal inside length of the box.

5. The method of locking the members of a laminated box which comprises the steps of erecting the box with inner side wall members of normal length having attached thereto inner bottom members of abnormal length; and with inner end wall members of abnormal width; locking the inner bottom members under the inner end wall members and locking the inner end wall members by the inner side wall members.

6. In a laminated box, made from an integral blank, a bottom member attached to a side wall member, said bottom member extending under an end wall member and locked in position thereby; said end wall member projecting past said side wall member and locked in position thereby.

HENRY KONDOLF.
